US0D1054327S

(12) **United States Design Patent** (10) Patent No.: **US D1,054,327 S**
(45) Date of Patent: ** Dec. 17, 2024

(54) **ELECTRIC SCOOTER**

(71) Applicant: **Brightway Innovation Intelligent Technology (Suzhou) Co., Ltd., Suzhou (CN)**

(72) Inventor: **Ruichen Zeng, Jiangsu (CN)**

(**) Term: **15 Years**

(21) Appl. No.: **35/519,199**

(22) Filed: **Aug. 11, 2023**

(80) **Hague Agreement Data**

Int. Filing Date: **Aug. 11, 2023**

Int. Reg. No.: **DM/233267**

Int. Reg. Date: **Aug. 11, 2023**

Int. Reg. Pub. Date: **Dec. 1, 2023**

(30) **Foreign Application Priority Data**

CLAIM

The ornamental design for an electric scooter as shown and described.

DESCRIPTION

1.1 is a front and left side perspective view of an electric scooter embodying my new design;
1.2 is a front elevation view thereof;
1.3 is a rear elevation view thereof;
1.4 is a top plan view thereof;
1.5 is a bottom plan view thereof;
1.6 is a right side elevation view thereof; and
1.7 is a left side elevation view thereof.
